United States Patent Office

Des. 223,496
Patented Apr. 25, 1972

223,496

ELECTRONIC TELEPHONE ANSWERING UNIT

Francis A. Foresta, 15727 Texaco,
Paramount, Calif. 90723

Filed Mar. 4, 1971, Ser. No. 121,244

Term of patent 14 years

Int. Cl. D14—03

U.S. Cl. D26—14

FIG. 1 is a front perspective view of an electronic telephone answering unit showing my new design;

FIG. 2 is a side perspective view thereof; and

FIG. 3 is a rear perspective view thereof.

I claim:

The ornamental design for an electronic telephone answering unit, substantially as shown.
